Attorneys.

UNITED STATES PATENT OFFICE.

JOHN H. VIEWEGH, OF INDIANAPOLIS, INDIANA.

PLANT STAND.

Application filed September 5, 1925. Serial No. 54,629.

The object of this invention is to provide an inexpensive and durable stand for supporting palms and other floral displays, which are used extensively for interior, as

5 well as exterior decorations, and a particular object is to provide such a stand, a large number of which can be nested in a small compact package for transportation from the florist establishment to the customer, and re-

10 turn, as well as for storage when not in use.

I accomplish the foregoing objects by the construction illustrated in the accompanying drawing, in which, Fig. 1, is a perspective view of a stand of my preferred form, Fig.

15 2, is a perspective view of a half dozen of my improved stands as same appear when nested for transportation or storage, and Fig. 3 is a perspective view of a modified form of stand.

20 Like characters of reference indicate like parts in the several views of the drawing.

The top 4 of the stand is preferably triangular in shape, and is formed out of sheet metal with the edges bent down on all three

25 sides to form marginal flanges 5.

The legs 6 are made out of metal angle bars of suitable length and bent outwardly at their lower portions to increase the area of the stand base and to facilitate the intro-

30 duction of one stand into the next in nest-

ing. The legs are attached to the outside of the respective corners of the angular top by spot-welding, the angle of the top fitting into the angle of the leg and permanently closing the joint between adjacent flanges

35 5 when the contacting parts are spot-welded together.

Brace-bars 7 connect each leg with those next it. The bars are preferably placed

40 against the inner sides of the legs at a suit-

able distance above the floor.

As above constructed, the comparatively small top 4 is well covered by a flower pot placed thereon, particularly with a trian-

45 gular top, thereby obviating the necessity of a mat to hide the top, and the three corner

extensions of the top give adequate support to the pot.

The stands are nested by dropping one stand down over the top of the next, in the manner illustrated in Fig. 2 which shows six stands nested together.

In the modification shown in Fig. 3, the top 4 is omitted and the upper ends of the legs are connected by metal bars 8, similar to the lower bars 7.

It is obvious that other variations may be made without departing from the spirit of my invention and I therefore do not desire to be limited, any more than is required by the appended claims.

I claim:

1. A flower stand comprising downwardly spreading legs each formed out of an angle bar placed with the inner angle of the bar toward the center of the stand, and an angular sheet metal top having its edges bent down between the angles of the top to form marginal flanges, the angles of the top being inserted in the corresponding angles of the legs with the legs outside of the flanges and lapping and closing the joints between the flanges the space between the spread legs being ample and unobstructed such that the stands may be freely nested in and on one another for the major portions of their lengths without reducing the space between the legs of the inner stands.

2. A flower stand comprising three downwardly spreading legs each formed out of an angle bar with the angle turned inwardly of the stand, and a plurality of leg connecting members between each pair of legs, and contained within the area bounded by the legs and uniting all of the legs into a rigid unit, one of said connecting members between each pair of legs being located at the upper ends of said legs the space between the spread legs being ample and unobstructed such that the stands may be freely nested in and on one another for the major portions of their lengths without reducing the space between the legs of the inner stands.

In testimony whereof I affix my signature.

JOHN H. VIEWEGH.
